UNITED STATES PATENT OFFICE.

ERNIE ADAMSON, OF CARROLLTON, GEORGIA.

ACETYLENE-GENERATOR.

1,079,823.

Specification of Letters Patent.

Patented Nov. 25, 1913.

Application filed February 19, 1913. Serial No. 749,503.

To all whom it may concern:

Be it known that I, ERNIE ADAMSON, a citizen of the United States, residing at Carrollton, in the county of Carroll and State 5 of Georgia, have invented new and useful Improvements in Acetylene-Generators, of which the following is a specification.

The invention relates to generators, and more particularly to the class of acetylene 10 generators.

The primary object of the invention is the provision of an acetylene generator wherein the bell is fixedly and detachably mounted within the tank to permit the ready 15 mounting of the same therein or its removal therefrom, the bell being equipped to carry the carbide holder and water admitting receptacle.

A further object of the invention is the 20 provision of an acetylene generator wherein the carbide holder is removably held within a water receptacle which is detachably hung within the bell and is so arranged with relation thereto as to prevent the choking 25 of the gas delivery pipe or the stopping up of the same.

A still further object of the invention is the provision of an acetylene generator wherein the tank carries resilient fingers 30 adapted to act upon the bell to properly center the same whereby it may be detachably fastened within the said tank in a quick and convenient manner.

A still further object of the invention is 35 the provision of an acetylene generator which is extremely simple in construction, thoroughly reliable and efficient in operation, and inexpensive in manufacture.

With these and other objects in view, the 40 invention consists in the construction, combination and arrangement of parts as will be hereinafter fully described, illustrated in the accompanying drawing, and pointed out in the claims hereunto appended.

45 In the drawings:—Figure 1 is a vertical longitudinal sectional view through an acetylene gas generator constructed in accordance with the invention. Fig. 2 is a sectional view on the line 2—2 of Fig. 1. 50 Fig. 3 is a sectional view on the line 3—3 of Fig. 1. Fig. 4 is a fragmentary perspective view of the tank body and top raised therefrom. Fig. 5 is a fragmentary sectional view through the fastener for the

water admitting receptacle carried by the 55 bell.

Similar reference characters indicate corresponding parts throughout the several views in the drawing.

Referring to the drawing by numerals, 60 the acetylene generator comprises a cylindrical tank 5 preferably constructed of metal, although it may be made of any other suitable material, and has its upper open end closed by means of a removable 65 cover or top 6 formed with a depending marginal flange 7 provided at intervals with inwardly extending locking lugs 8 which are adapted to engage the cam faces of ribs or flanges 9 formed on the outer face of the 70 tank 5 at the open end thereof, the ribs or flanges 9 being separated to form entrance spaces 10 for the lugs 8 whereby on telescoping the cover or top 6 upon the tank 5 the lugs 8 will pass through the spaces 10 75 to engage the cam surfaces of the ribs or flanges 9 so that on the turning of the cover or top 6 the same can be locked upon the tank and thereby effect a fluid-tight closure for the open end of the said tank, the latter 80 being partially filled with water through the open end thereof on the removal of the cover or top therefrom. Tapped or otherwise mounted in the side wall of the tank 5 is a drain cock 11 which is located contiguous to the bottom of the tank 5 so as to 85 permit the proper draining of the tank and the removal of sediment or foreign matter therefrom.

Arranged within the tank 5 spaced from 90 the top or cover 6 is a stationary ring 12 which is formed at intervals with legs or bosses 13 extending radially therefrom at the outer periphery thereof, each boss or leg being provided with a seat 14 in which 95 is fitted one end of a spring finger 15 which depends into the lower portion of the tank 5, the ring 12 being positioned concentrically to the center of the tank 5 by the legs or bosses 13, and is secured therein through the 100 medium of the screw fasteners 16 which pass through the tank 5, fingers 15 and engage in the legs or bosses 13 as shown, the spring fingers 15 being designed for a purpose presently described.

105 Removably fitted in the tank 5 is a cylindrical shaped gas bell 17 provided with a closed top 18, while its opposite lower end

is open, the bell being fastened at its closed top 18 to an upwardly arched spider 19 formed with an externally threaded rim 20, the ring 12 being internally threaded for 5 the detachable engagement of the rim 20 of the spider therewith. The bell 17 has its open end terminating close to the bottom of the tank 5, while mounted in the side wall of the said gas bell near the closed top 18 thereof are holding pins or lugs 21 for the detachable engagement therewith of a receptacle or cup 22 which is formed with a flared open end 23 provided at intervals with bayonet shaped slots 24 receiving the 10 lugs or pins 21, the cup or receptacle 22 being turned slightly whereby the said pins or lugs 21 will engage in the closed ends of the slots 24 for the secure fastening of the cup or receptacle within the gas bell 17 as shown. 15 20 The flared end 23 of the receptacle or cup 22 forms a bearing or annular seat 25 for the flared mouth 26 of a carbide holder 27 which is readily removable from the cup or receptacle when the same is detached and 25 removed from the bell 17, the cup 27 depending within the cup or receptacle 22 and is formed with a screened opening 28 centrally in its bottom for communication with the cup or receptacle 22 whereby water entering the latter may pass through the opening 28 into the holder 27 for action upon the carbide which is held therein to produce 30 35 gas.

Extending upwardly between the bell 17 and the cup or receptacle 22 is the vertical portion 29 of a gas delivery pipe which has its horizontal portion 30 passed through the tank 5 exteriorly thereof, the pipe being fastened or coupled to the tank 5 in any 40 desirable manner, and the vertical portion 29 thereof terminates slightly spaced from the flared end 23 of a cup or receptacle 22 so that gas circulating between the latter and the bell 17 will flow into the pipe and be 45 delivered thereby to any suitable point, the spring fingers 15 being arranged in downwardly converging relation so as to act upon the bell 17 when inserted through the ring 12 in the tank 5 for the centering of the said bell to permit the quick and easy mounting and fastening of the bell in position in the 50 tank.

Rising centrally from the spider 19 is a stem 31 which terminates in a cross handle 55 32, the same being spaced from the top or cover 6, and this handle 32 permits the fastening of the rim 20 of the spider in the ring 12, or the unfastening of the said rim therefrom, it being seen that the gas bell 17 60 can be stationarily mounted in the tank 5 or removed therefrom.

In the operation of the acetylene generator, the carbide is placed within the holder 27 which is inserted within the cup or recep-

tacle 22 so that its flared mouth 26 will rest 65 on the seat 25 formed in the said cup or receptacle and thereafter the latter is fastened in the bell 17 which is then stationarily mounted in the tank 5, the same being 70 properly filled with water prior to the fastening of the cover or top 6 thereon. The cup or receptacle 22 at diametrically opposite points is formed with downwardly tapered slots 33 through which the water passes from the tank 5 into the said cup or 75 receptacle 22 and as the water rises therein it will be admitted through the opening 28 in the carbide holder 27 to act upon the carbide therein for the generation of gas. During the generating of the gas the pressure 80 thereof will act upon the body of water, causing it to lower within the cup or receptacle 22 by driving the water therefrom back into the tank, the gas escaping from the said cup or receptacle 22 above the water 85 level into the space between the bell 17 and the said cup or receptacle, whence the gas will flow into the vertical portion 29 of the pipe and be delivered through the horizontal portion 30 thereof to any suitable 90 point for consumption. When the gas generated becomes low in quantity the water rises within the receptacle or cup 22 to mix with the carbide in the holder 22 thereby further generating gas until the pressure thereof reaches a predetermined degree, whence the water will be again disturbed and forced from the receptacle or cup 22 to permit the gas to escape therefrom and be discharged 95 through the pipe as heretofore stated. The 100 cup or receptacle 22 serves to catch sediment or minute particles of carbide, and in this manner the tank will remain clean and also the cup can be readily washed or cleaned 105 when the bell is removed from the tank.

From the foregoing it is thought that the construction and manner of operation of the device will be clearly understood, and therefore a more extended explanation has been omitted.

What is claimed is:—

1. In an acetylene generator, a tank, a supporting ring fixed interiorly thereof, a gas bell detachably engaged with the ring and depending within the tank, a slotted cup detachably engaged interiorly of the bell and having its major portion spaced therefrom, a carbide holder removably held within the cup, means extending between the cup and bell and leading from the tank 115 for delivering gas from the bell to a point exteriorly of the tank, and means integrally formed with the bell for permitting the turning thereof for the fastening of the same in the ring or detaching it therefrom. 120
2. In an acetylene generator, a tank, a supporting ring fixed interiorly thereof, a gas bell detachably engaged with the ring 125

and depending within the tank, a slotted cup detachably engaged interiorly of the bell and having its major portion spaced therefrom, a carbide holder removably held 5 within the cup, and means extending between the cup and bell and leading from the tank for delivering gas from the tank.

In testimony whereof I affix my signature in presence of two witnesses.

ERNIE ADAMSON.
